UNITED STATES PATENT OFFICE.

JOSEPH GRANZ, OF DULUTH, MINNESOTA.

MOTION-PICTURE MACHINE.

1,349,420.

Specification of Letters Patent. Patented Aug. 10, 1920.

Application filed March 28, 1919. Serial No. 285,758.

To all whom it may concern:

Be it known that I, JOSEPH GRANZ, a native of Austria, who has declared his intention of becoming a citizen of the United States of America, and a resident of Duluth, in the county of St. Louis, State of Minnesota, have invented certain new and useful Improvements in Motion-Picture Machines, (Case 1,) of which the following is a specification:

This invention relates to the intermittent film feeding type of motion picture machines, and has for its objects:

To provide a structural formation and association of parts wherein the different members of the intermittent film feeding mechanism are mounted together as an individual unit, and detachable from the main frame as a complete unit for repair readjustment and replacement in a rapid, convenient and effective manner.

To provide a simple and effective operative connection between the aforesaid intermittent film feeding mechanism and the correlated light shutter, film feed, film take-up and film reeling mechanisms, by means of which the operations of the mechanisms are effected and controlled in a convenient and efficient manner.

To provide in connection with the said intermittent film feeding mechanism and its associated aperture plate, a simple and effective means for attaining a proper framing of the picture film at the light aperture of said plate, all as will hereinafter more fully appear.

In the accompanying drawings:

Figure 1, is a side elevation of a motion picture machine and accessories, showing the general arrangement and connections of the different parts and mechanisms.

Fig. 2, is an enlarged side elevation of the central portion of the machine, showing the driving connections between the film feeding mechanisms, etc., the inclosing shell or housing thereof being shown in section.

Fig. 3, is an enlarged vertical section through the central portion of the machine adjacent to the optical center thereof, made in a direction the reverse of Figs. 1 and 2, and showing the relative arrangement of the present film feeding mechanism to the film guide and aperture plate.

Fig. 4, is an enlarged fragmentary sectional elevation, on line x^4-x^4 , Fig. 1. 55

Fig. 5, is a similar view on line x^5-x^5 , Fig. 1.

Fig. 6, is a detail perspective view of the driven element and its associated parts of the intermittent film feeding mechanism. 60

Fig. 7, is a similar view of the driving element and its associated parts of said mechanism.

Like reference numerals indicate like parts in the several views. 65

Referring to the drawings, 1 designates the main casing of the machine, preferably of the rectangular box form shown, and forming the main chamber of the machine, adapted to contain the film actuating drums, 70 film guiding means, etc., and provided at one side with a shell or casing 2 of a cup form adapted to provide a containing chamber for the interconnected operating gears of the machine hereinafter described 75 in detail.

3 and 4 designate the respective upper and lower film magazines of the usual drum form and adapted to receive in a removable and replaceable manner the film reels 5 and 6 of the machine. Said film magazines are fixedly secured to upper and lower saddle formations 3' and 4' on the respective top and bottom portions of the main casing 1, and are provided with tangentially arranged film apertures which open into the main chamber aforesaid, in vertically alined relation to the film supply and film take-up drums of the machine, hereinafter described in detail. 90

7 designates angle-brackets fixed on the lower magazine 4 and adapted to receive the adjustable tripod feet 7' by which the apparatus is supported as a whole.

8 designates the objective or front lens member of the machine, attached to the front wall of the main casing 1 in a position which brings the optical center of the machine at the mid-height and mid-width of the main chamber of the casing 1. 95

9 designates the condenser or rear lens member of the machine, of any usual construction, the carrying frame of which is secured to the rear wall of the main casing 1 by horizontal posts 10, as set forth in detail in my companion application for Let- 100
105

ters Patent, Serial No. 285,760, filed March 28, 1919.

11 designates an apertured shell secured within the main chamber of the casing 1 and to the rear wall of the same, with its aperture on the optical center of the machine.

12 designates a hinged gate of a plate form associated with the aperture of the shell 11 and having an operating shaft extending outside the main casing 1 for convenient manual operation when it is desired to cut-off the light rays from the usual apertured guide plate of the picture film, as 15 a fire preventative precaution in the practical operation of the machine.

13 designates a transversely arranged fixed shaft or arbor carrying the driving member of the intermittent film feeding mechanism hereinafter described. When the machine is hand driven the gear wheel 14 mounted on the shaft 13 receives motion through gears 15, 16, 17 and 18 from a transverse shaft 19 provided with an operating hand crank. When the machine is power driven the gear 14 aforesaid receives motion through gear 15 aforesaid, idler gears 20, and 21 on countershafts 22, 23 and pulley and endless belt connection 24 between the countershaft 23 aforesaid, and an operating motor 25 secured to the underside of the lower film magazine 4. The motor 25 is preferably of the electric type and provided with a controlling rheostat 26 and other usual accessories, while the endless belt connection 24 is provided with the usual tightener mechanism 27 by which its operativeness is controlled.

28 designates a transverse shaft carrying the film supply sprocket drum 29 of the machine, and receiving motion from the shaft 19 through the gears 18 and 30, as shown in Fig. 2.

31 designates a transverse shaft carrying the film take-up drum 32 of the machine and receiving motion from the shaft 19 through the train of idler gears 33 as shown.

34 designates a longitudinally arranged shaft carrying at its forward end the light shutter 35 of the machine and receiving motion from the gear wheel 15 aforesaid, through a pinion 36 and spiral gears 37, as shown in Fig. 2. Said light shutter is preferably of the usual radial bladed type and 55 is arranged to the front of the objective 8 aforesaid.

In the present structure the film supply sprocket drum 29 is arranged in the upper rear portion of the main chamber of the casing 1, while the film take-up sprocket drum 32 is arranged in the lower rear portion of said main chamber and in vertical alignment with the film apertures of the magazines 3 and 4 heretofore described and 65 said sprocket drums are provided with the

usual spring held bearing rollers by which the picture film is held in proper operative engagement with said drums 29 and 32.

38 designate guide throats formed by opposed pads of fibrous or like elastic material and arranged at the above mentioned film apertures of the magazines 3 and 4, and adapted to prevent a local combustion of the picture film within the main chamber of the casing 1, extending into the respective magazines. 70 75

39 designates a vertically movable slide arranged in guides on a side wall of the main casing 1 and provided with an operating lever 40 extending outside said casing for 80 convenient manual actuation.

41 designates a drum revolvably mounted on the slide 39 and adapted to engage a loop in the picture film intermediate of the apertured guide plate and the intermittent 85 film feeding drum heretofore referred to. The construction is such that a downward adjustment of the drum 41 is adapted to effect an independent movement of the picture film past the light aperture of said 90 guide plate to effect a proper framing of the pictures on said film.

42 designates an endless belt forming a driving connection between belt pulley on the shaft 31 of the film take-up drum 32 95 and a belt pulley on the carrying shaft 43 of the lower film reel 6, as shown in Fig. 1.

44 designates a belt tightener mechanism associated with the aforesaid endless belt 42 and adapted to render the same operative during a film rewinding operation of the machine. 100

45 designates the apertured guide plate of the machine, arranged on the optical center of the machine and intermediate of and a short distance in front of the film supply and film take-up drums 29 and 32 aforesaid. Said aperture plate 45 is provided with the usual spring gate 46 preferably of the construction set forth and claimed in my companion application for Letters Patent, Serial No. 285,759, filed March 28, 1919, and by means of which the picture film is guided in a flat condition past the light aperture of the plate 45 aforesaid. 105 110 115

47 designates the lamp house of the machine, preferably of the detachable construction set forth and claimed in my aforesaid application, Serial No. 285,760, so that the same lamp house may be removed from 120 its motion picture position shown in Fig. 1 and applied to and used in connection with the condenser 48 of a stereopticon or like projecting apparatus 49 mounted on one side of the upper film magazine 3, as illustrated in said Fig. 1. 125

A material part of the present invention involves the mounting of the parts of the intermittent film feeding means as a single unit, demountable and replaceable as a 130

whole, in place in the main casing of the machine, and to such end comprises a structural arrangement as follows:—

50 designates a base or bracket plate, 5 adapted to be removably secured by screws 51 or the like to a side wall of the casing 1 and over a passageway in said wall through which the inner portion of the mechanism carried by the plate 50 is introduced into 10 place in the main chamber of the casing 1. The plate 50 carries the before mentioned fixed transverse shaft 13 upon which the driving member of the intermittent film feeding mechanism is revolubly mounted. In 15 the structure shown said driving member comprises the before mentioned gear 14, a balance wheel 52 and the mutilated pin carrying driving member or disk 53, fixedly secured together upon a bushing 54 forming 20 the bearing for said parts upon the aforesaid shaft or arbor 13 as shown in Figs. 4, 5, 6 and 7.

55 designates a bearing bushing extending through an orifice in the base plate 50 aforesaid, and provided with an external collar 56 intermediate its length and adapted for abutment against the face of the base plate 50.

57 designates a confining plate or bar removably secured to the base plate 50, and adapted to bear against one side of the collar 56 to clamp and hold the bearing bushing 55 in place.

58 designates a shaft extending through 35 the bore of the bushing 55 and having bearing therein, with one end carrying the intermittent film feeding sprocket drum 59 of the machine, while the other end carries the radially slotted disk 60 which constitutes 40 the driven member of an intermittently operating gearing of the well known Geneva form.

Having thus fully described my said invention what I claim as new and desire to 45 secure by Letters Patent, is:—

1. In a motion picture machine, a main casing formed with an opening in its side wall, and an intermittent film feeding mechanism comprising a carrying base detachably secured to said casing over said opening, an arbor fixed on said supporting base, a driving intermittent gear member and its associated pinion revolubly mounted on said arbor, a journal bushing secured to said supporting base, a shaft journaled in said bushing, a film feeding drum mounted on one end of said shaft, and a driven intermittent gear member mounted on the other end of said shaft, substantially as set forth.

2. In a motion picture machine, a main casing formed with an opening in its side wall, and an intermittent film feeding mechanism comprising a carrying base detachably secured to said casing over said opening, an arbor fixed on said supporting base,

a driving intermittent gear member and its associated pinion and balance wheel revolubly mounted on said arbor, a journal bushing secured to said supporting base, a shaft journaled in said bushing, a film feeding 70 drum mounted on one end of said shaft, and a driven intermittent gear member mounted on the other end of said shaft, substantially as set forth.

3. In a motion picture machine, a main 75 casing formed with an opening in its side wall, and an intermittent film feeding mechanism comprising a carrying base detachably secured to said casing over said opening, an arbor fixed on said supporting base, 80 a driving intermittent gear member and its associated pinion revolubly mounted on said arbor, a journal bushing fitting an orifice in said supporting base and provided with a peripheral collar, a clamp plate secured to 85 said supporting base and having engagement with said collar, a shaft journaled in said bushing, a film feeding drum mounted on one end of said shaft, and a driven intermittent gear member mounted on the other 90 end of said shaft, substantially as set forth.

4. In a motion picture machine, a main frame or casing, a film supply drum and a film take-up drum mounted in vertically alined relation in said frame, a guide plate 95 formed with a light aperture and arranged intermediate of said drums, an intermittent film feeding mechanism formed as a unit and detachably connected to said main frame and arranged in front of the film supply and 100 take-up drums aforesaid, a vertically adjustable drum arranged intermediate of the guide plate and intermittent film feeding mechanism aforesaid and adapted to engage a loop in the picture film to effect a framing 105 of the same, and means for imparting simultaneous rotation to the film supply, film take-up and film feed drums and mechanism, substantially as set forth.

5. In a motion picture machine, a main 110 casing of a rectangular box shape open at top and bottom, the side walls of the casing having saddle extensions at their upper and lower ends, upper and lower film magazines having circular walls fitting the aforesaid 115 saddle extensions of the side walls of the casing and forming closures for the upper and lower open ends of said casing, a film supply drum and a film take-up drum mounted in vertically alined relation in said 120 casing, a film guide plate formed with a light aperture and arranged intermediate of said drums, an intermittent film feeding mechanism arranged to the front of the film take-up drum aforesaid, and means for imparting simultaneous rotation to the film supply, film take-up and film feed drums and mechanism aforesaid, substantially as set forth.

6. In a motion picture machine, a main 130

casing of a rectangular box shape open at top and bottom, the side walls of the casing having saddle extensions at their upper and lower ends, upper and lower film magazines having circular walls fitting the aforesaid saddle extensions of the side walls of the casing and forming closures for the upper and lower open ends of said casing, bracket

lugs carried on the lower film magazine, tripod legs attached to said bracket lugs, and 10 film actuating means arranged in said main casing, substantially as set forth.

Signed at Duluth, Minn., this 24th day of March, 1919.

JOSEPH GRANZ.
